UNITED STATES PATENT OFFICE.

MORTIMER J. CLARK, OF SUMMITVILLE, COLORADO.

COMBINED WATCH-POCKET AND WATCH-GUARD.

SPECIFICATION forming part of Letters Patent No. 606,275, dated June 28, 1898.

Application filed July 22, 1897. Serial No. 645,544. (No model.)

To all whom it may concern:

Be it known that I, MORTIMER J. CLARK, a citizen of the United States, residing at Summitville, in the county of Rio Grande and State of Colorado, have invented certain new and useful Improvements in a Combined Watch-Pocket and Watch-Guard; and I do declare the following to be a full, clear, and exact description of the invention, such as will 5 enable others skilled in the art to which it app pertains to make and use the same, reference being had to the accompanying drawings, and to the figures of reference marked thereon, which form a part of this specification.

15 My invention has relation to combined watch-pockets and watch-guards; and it consists in the novel construction and arrangement of its parts, as hereinafter described.

The object of the invention is to provide a 20 watch-pocket which is dust-proof and waterproof, said pocket being provided with a lock which is adapted to be operated by a combination and adapted to securely hold the watch in place in the pocket and prevent its being 25 taken or falling from the pocket without first operating the combination of the lock.

The further object of the invention is to provide an alarm in connection with the lock, said alarm adapted to be sounded in case the 30 combination is not properly worked or in the event that an attempt is being made surreptitiously to remove the watch from the pocket.

The further object of the invention is to provide a simple and effective means for operating the combination and for opening the 35 pocket when the combination is properly adjusted.

In the accompanying drawings, Figure 1 is an elevation of the device, partly in section. 40 Fig. 2 is a horizontal sectional view of the combination lock and alarm. Fig. 3 is a perspective view of the back of the framework or plates of the device. Fig. 4 is a perspective view of the bolt used in connection with the combination-lock.

The frame or base plate of the device consists of the bail 1, said bail having at suitable intervals the sharpened protrusions 2, the upper portion of the bail being provided with 45 the semicircular recess 3. The protrusions 2 are adapted to pass through the material of the vest of the wearer of the device, the

said protrusions being clenched on the inside of the garment. The bail 4 is hinged at its lower end to the ears 5 of the bail 1. Said 55 bail 4 is provided with the semicircular recess 6, which is adapted to register with the semicircular recess 3 of the bail 1. The coiled spring 7 (see Fig. 2) is wound about the pin, forming the pivotal connection between the plates 1 and 4, said spring being adapted to automatically throw the bail 4 open when it is desired to remove the watch. The pocket 8 is made of chamois or any other suitable material. Said material may be made 65 waterproof, if so desired. The pocket is attached at its upper edges to the bails 1 and 4 by any suitable means. The pocket is adapted to hold the watch, as shown in Fig. 1, the stem of the watch passing between the recesses 3 and 6. The pocket 8 is adapted to slip in the vest-pocket of the wearer.

The bolt 9 is suitably housed at the ends of the bails 1 and 4. Said bolt is provided at its upper end with the button 10, said button 75 extending above the housing of the bolt. The bolt is provided at its lower end with the shank 11, about which is located the coiled spring 12, said coiled spring resting at its lower end on the bottom of the housing for 80 the bolt and at its upper end bearing against the under side of the bolt. The tendency of said spring is thus to keep the bolt up. The bolt is provided near its upper end with the inclined section 13, and immediately behind 85 said section is located a recess 14. The bail 4 is provided at its edge with a protrusion 15, said protrusion being adapted to come in contact with the inclined section 13 and depress the bolt. The said protrusion 15 then enters 90 the recess 14. The bolt is then forced up by means of the spring 12, and thus the bails 1 and 4 are securely held together.

The bolt 9 is provided with the transverse perforation 16 and the diagonally-inclined 95 perforation 17. The functions of these perforations will be hereinafter stated.

The combination lock and alarm consists of the casing 18, on the face of which is located a clock-dial 19. Any other suitable dial 100 may be substituted in place of that shown in Fig. 1. The bell is located in the interior of the casing 18. The pin 21 passes through the center of the bell and is secured to the bell.

The lower end of the pin 21 is journaled in the casing, as shown in Fig. 2. The bell is provided with a recess 22, in which is located a spring 23, one end of said spring being secured to the pin 21 and the other end of the spring being secured to a stationary point on the bottom of the casing 18. The central post of the bell is provided with a recess 24. The inner side of the bell is provided with a number of protrusions 25, located at suitable intervals, as shown in Fig. 2. The revolving section 26 is loosely mounted on the pin 21. Said section is provided at its outer end with a dial-face 27. The outer end of the pin 21 is provided with a milled head 28, and on the head is located the indicator-point 29. The section 26 is provided with a recess 30. The dog 31 enters at its inner end the interior of the bell 20. The point 32 of the said dog is adapted to enter the recesses 24 and 30 when the said recesses register with each other, as shown in Fig. 2. The guide 33 retains the dog 31 in its proper position. The dog 31 is provided with a pawl 34, said pawl 34 being adapted to engage the protrusions 25 of the bell, and thus the bell is prevented from revolving. The outer end of the dog 31 passes through the perforation 16, and the pin 35 extends through the outer end of the dog 31, said pin being located in the inclined perforation 17.

The device is operated as follows: The parts being in the position as shown in Fig. 1, the dial-section 26 is shifted until its recess 30 is brought opposite the end 32 of the dog. By revolving the pin 21 the recess 24 of the bell is made to register with the recess 30—that is, the recesses 24 and 30 are brought directly opposite the end 32 of the dog. The bolt 9 is then depressed, and the pin 35, rising in the inclined perforation 17, causes the dog 31 to move laterally. This throws the end 32 in the recesses 24 and 30, and thus the bell 20 is prevented from revolving, and the protrusion 15 is carried above the inclined section 13 of the dog, and the spring 7 automatically throws the bail 4 open. Thus the watch may be removed. In order to secure the watch, it is replaced in the pocket 8. The bail 4 is closed. The protrusion 15, coming in contact with the inclined section 13, forces the dog down, and when the said protrusion 15 is above the recess 14 the spring 12 elevates the dog, and thus the watch is secured. The dial-section 26 and the pin 21 are then given a half-turn, and thus the recesses 24 and 30 are carried away from the inner end 32 of the dog.

Should a person who is not familiar with the combination attempt to remove the watch from the pocket, he would depress the dog 9, and as the recesses 24 and 30 would not be opposite the inner end 32 of the dog the dog 21 would be moved laterally until the end 32 came in contact with the side of the section 26 or the side of the bell-post. This would not sufficiently liberate the protrusion 15 from the recess 14, but it would be sufficient to dis-

engage the pawl 34 from the protrusions 25, and as the end 32 of the dog does not enter the recess 24 the milled spring 23 will cause the bell 20 to revolve rapidly, and the clapper 36, coming in contact with the protrusions 25, will cause the bell to ring. Thus the wearer will know that his watch is being tampered with. By changing the position of the indicator-point 29 the combination of the device may be varied to suit.

Having thus described my invention, what I claim as new, and desire to secure by Letters Patent, is—

1. In a device such as described consisting of a suitable means for holding the watch, a longitudinally-moving bolt adapted to secure said means in its closed position, a combination alarm and lock attached to said bolt, a bell located in the interior of said lock and alarm, said bell having a recess, a dial located on the casing of the lock, a dial-section adapted to coact with the dial on the casing said section having a recess, the recess of said section adapted to register with the bell-recess, a longitudinally-moving dog adapted to enter at its inner end the registering recesses of the bell and the dial-section, said dog adapted to be shifted laterally as the bolt is depressed, and a clapper suitably mounted and adapted at intervals to sound the bell.

2. In a device such as described, a receptacle adapted to contain the watch, a combination lock and alarm attached to the device, a dog entering said combination lock and alarm, a longitudinally-moving bolt adapted to secure the receptacle in its closed position, the dog passing through a perforation in said bolt, said bolt having an inclined perforation, an arm passing through the end of the dog and being located in said inclined perforation of the bolt.

3. In a device such as described, a suitable means for holding the watch, a suitable means for retaining the watch containing means in its closed position, a combination alarm and lock consisting of a bell, a revolving pin attached to said bell, a spring adapted to revolve said pin, said bell having a recess, protrusions located on the inner side of the bell, a dog adapted to enter at its inner end the recess of the bell, a pawl located on said dog and adapted to engage the protrusions of the bell, a clapper suitably located and adapted to come in contact with the protrusions of the bell as the bell is revolved, a suitable means for operating the dog.

4. In a device such as described, a bell having in its interior a recess, a suitable means for revolving said bell, protrusions located on the inner surface of the bell, a dog adapted to enter at its inner end the recess of the bell, a suitable means for operating said dog, a pawl located on said dog and adapted to engage the protrusions of the bell, a clapper suitably located and adapted to come in contact with the protrusions of the bell as the bell is revolved.

5. In a device such as described, a bell adapted to revolve, a casing inclosing said bell, a dial located on said casing, a dial-section adapted to revolve within the casing, the dial-section and the bell each having a recess, said recesses adapted to register, a longitudinally-moving dog entering said bell, a suitable means for operating said dog, the inner end of said dog adapted to enter the registering recesses of the dial-section and the bell, and a clapper suitably mounted and adapted to come in contact with the bell.

6. In a device such as described, a bell adapted to revolve, a pin fixed to the center of said bell, a casing inclosing said bell, a dial located in said casing, said dial having a re-

cess, an indicator-section adapted to revolve in the casing, said section having a recess, a recess of the section adapted to register with the recess of the bell, an indicator-point located on the bell-pin, a dog entering said bell, said dog adapted at its inner end to enter the recesses of the dial-section in the bolt and suitable means for operating the dog, and a clapper suitably mounted and adapted to come in contact with the bell.

In testimony whereof I affix my signature in presence of two witnesses.
